[57] CLAIM

The ornamental design for a gaming machine, substantially as shown and described.

DESCRIPTION

FIG. 1 is a perspective view of a gaming machine showing the front, top and right side of our new design; FIG. 2 is a front elevational view of the gaming machine shown in FIG. 1;

FIG. 3 is a right side elevational view of the gaming machine shown in FIG. 1, the left side being a mirror image thereof;

FIG. 4 is a top plan view of the gaming machine shown in FIG. 1; and

The back and bottom of the gaming machine shown in FIG. 1 are substantially plain.
